Ernest Wuerfel
BY *Paul Goepel.*

ATTORNEY

UNITED STATES PATENT OFFICE.

ERNEST WUERFEL, OF NEW YORK, N. Y.

BUTTON.

SPECIFICATION forming part of Letters Patent No. 281,425, dated July 17, 1883.

Application filed November 22, 1881. Renewed December 18, 1882. (No model.)

To all whom it may concern:

Be it known that I, ERNEST WUERFEL, of the city, county, and State of New York, have invented certain new and useful Improvements in Buttons, of which the following is a specification.

This invention has reference to an improved button for clothing of all kinds, which can be readily attached without punching holes 10 through the cloth, and which is reliably held in position without any possibility of becoming detached.

The invention consists of a button the head of which is made of three parts—a face-plate, 15 an intermediate recessed spring-plate having a tubular shank through which the post of the base-plate or shoe of the button is inserted, the post being engaged by the interior ends of the recessed spring-plate below the conical head 20 of the same.

In the accompanying drawings, Figure 1 represents a vertical central section of the head of my improved button. Fig. 2 represents a top view of the head; Fig. 3, a detail plan 25 view of the intermediate spring-plate of the button; Fig. 4, a detail side view of the base-plate or shoe, and Fig. 5 a vertical central section of the button as attached to the fabric.

Similar letters of reference indicate corresponding parts.

Referring to the drawings, A represents the head of my improved button, and B the shoe or base-plate of the same.

The head of the button is made of three 35 parts—a face-plate, a, which may be of any material, shape, or finish, an intermediate recessed spring-plate, b, and bottom plate, d, the latter being provided with a tubular shank, e. The connection of the face-plate a with the 40 bottom plate, d, is made by an annular overlapping flange of the former, which is tightly closed around the edge of the bottom plate d, as shown in Fig. 1, while the spring-plate b is 45 preferably retained by a flat contact portion of the face-plate, which bears on the exterior

portion of the spring-plate b, as shown clearly in Figs. 1 and 5.

The spring-plate b is provided with a central opening, b', and radial slits or recesses, so as to form two or more spring-teeth, b'', as 50 shown in Fig. 3.

To attach the button to the fabric the shank e of the head is passed through the same by means of a conically-tapering pin which is inserted into the shank, as shown in dotted lines 55 in Fig. 1. By this mode of piercing the fabric the punching of the fabric is dispensed with. When the shank of the head A has been passed through the fabric, the solid post f of the base-plate or shoe B is inserted into the tubular 60 shank e, and connected thereto by forcing the conical head f' of the post f through the central opening, b', of the spring-plate b, so that the ends of the spring-teeth b'' spring into an annular groove, f'', below the head f' of the 65 post f, as shown clearly in Fig. 5. When the post of the shoe is engaged in this manner by the teeth of the intermediate spring-plate, b, an absolutely reliable and permanent fastening for the button is formed, by which the 70 button is not only adapted for the manufacture of clothing, but also for domestic purposes.

Having thus described my invention, I claim as new and desire to secure by Letters Patent— 75

In a button, the combination of the head A, consisting of a face-plate, a, intermediate spring-plate, b, having a central opening, b', and teeth b'', and a bottom plate, d, having a tubular shank, e, with a shoe or base-plate, 80 B, having a center post, f, and an annular groove, f'', below the head f', substantially as set forth.

In testimony that I claim the foregoing as my invention I have signed my name in presence 85 of two subscribing witnesses.

ERNEST WUERFEL.
